CLOCK

Max E. Schlenker, Peru, Ill., assignor to General
Time Instruments Corporation, New York,
N. Y., a corporation of Delaware

Application April 12, 1943, Serial No. 482,698

11 Claims. (Cl. 58—16)

The present invention relates in general to clocks and more particularly to clocks of the alarm type. The main object of the invention is to provide an alarm clock having an improved alarm switch or shut-off mechanism.

According to one feature of the invention, the manual member which controls the alarm switch mechanism is arranged to be operated in the same direction irrespective of whether the alarm is being turned "on" or "off."

According to another feature of the invention, the manual member for controlling the alarm switch mechanism has means associated therewith for visually indicating whether the alarm mechanism is in "on" or "off" position.

Another feature of the invention relates to the means for holding the manual member in a partially operated position when the alarm mechanism is in "off" position.

The above and other objects and features of the invention will be clearly understood from a perusal of the following specification when read in connection with the accompanying drawings, comprising Figures 1 to 5, inclusive, in which

Fig. 1 is a cross sectional view of a clock embodying the present invention taken along line 1—1 of Fig. 2, some of the parts not essential to an understanding of the present invention having been omitted for clarity;

Fig. 2 is a plan view of the clock mechanism as viewed from the left in Fig. 1;

Fig. 3 is a cross sectional view of the time and alarm setting means;

Fig. 4 shows the alarm switch mechanism in "on" position; and

Fig. 5 shows the alarm switch mechanism in "off" position.

Referring now in detail to the drawings, only sufficient of the parts of a clock have been shown to clearly illustrate the present invention. The casing member of the clock is indicated by the reference character 1, the gong or back cover of the clock by the character 2, and the movement holder by the reference character 3.

Referring particularly to Figs. 1 and 2 of the drawings, the major portion of the clock movement is mounted between the front movement plate 5 and the rear movement plate 4, which plates are held in parallel spaced relationship by means of the pillars 7. Secured to the front movement plate 5 is the dial plate 6 which is held in spaced relationship thereto by means of the bent-up portions 79 of dial plate 6, these portions having reduced projections which fit into holes in the front movement plate 5. The move-

ment holder 3 is secured to the casing members of the clock in a manner not illustrated in the drawings and in turn mounts the clock movement. This movement holder is connected to the rear movement plate 4 by means of the spacing pillars 8. The gong 2 is mounted on the movement holder 3 by means of screws such as 9.

For the sake of clarity, the usual escapement mechanism, and spring and spring barrel have been omitted from the drawings since these may be of the usual construction as found in the ordinary clock.

The center shaft 46 is journaled in the two movement plates and passes through a bushing 15 in the dial plate 6. Fixedly mounted on this center shaft is the gear wheel 65 which is part of the setting mechanism for the hands, the collar 49 against which bears the friction spring 50, and the pinion 51 which is part of the 12 to 1 reduction gearing between the minute and hour hands. Also directly mounted on the center shaft 46 is the minute hand 56. The gear wheel 47 and associated pinion 48 are rotatably mounted on shaft 46, and are connected thereto through the friction connection comprising the spring 50 which bears against the end of pinion 48, and against the previously mentioned collar 49. The pinion 48 is geared to the usual spring barrel by means of which power is transmitted to the center shaft. The gear 47 is connected through the usual train to the clock escapement.

Referring particularly to Fig. 1, the 12 to 1 reduction gearing for the hour hand comprises the pinion 51 mounted on shaft 46 and geared into the wheel 73 mounted on shaft 75 together with the pinion 74. The pinion 74 is geared into the wheel 52 which is mounted on the hour sleeve which in turn is rotatably mounted on the center shaft 46. This hour sleeve extends through the dial plate 6 and at its outer end is mounted the hour hand 57. Surrounding the hour sleeve is another sleeve on which are mounted the alarm cam 55 and associated gear 54 which is provided for setting the alarm mechanism. This sleeve 45 also extends through the dial plate and at its outer end is mounted the alarm set indicating hand 58. The cam 55 is provided with a notch or cutaway portion 76 which is adapted to cooperate with the cam follower 53 which consists of a bent down portion cut out of the wheel 52. The follower 53 is maintained against the surface of the crown cam 55 by means of flat spring 59 mounted on the front movement plate 5. This flat spring is provided with a lateral projection 55 60 adapted to engage the teeth of the alarm

escape wheel 10 when the follower 53 is on the high portion of cam 55. When the follower drops into the notch 76 the projection 60 is withdrawn from the teeth of the escape wheel 10 and permits the alarm mechanism to function.

The alarm escape wheel 10 is mounted on shaft 11 which is journalled in the movement plates 4 and 5. The pinion 12 is fixedly mounted on shaft 11 to the rear of plate 4 and this pinion is adapted to engage a gear wheel (not shown) attached to the spring shaft. The power for operating the alarm mechanism, therefore, is transmitted from the drive spring to pinion 12. An alarm hammer 13 (Fig. 1) is mounted on shaft 16 which is journalled in the two movement plates. This hammer member consists of an extended arm carrying at its lower end the weighted hammer mechanism 14 which is adapted to strike against the gong 2 when the alarm mechanism is operated. This arm operates through a hole 15 in the movement holder 3.

The hammer member 13 is also provided with the pallets cooperating with the escape wheel 10 and an arm 41 extending upwardly from the member 13 and cooperating with the manual shut-off mechanism as will be explained later.

The manual alarm switch or shut-off mechanism includes a bell crank lever 36 fixedly mounted on shaft 35 journalled in the two movement plates. This bell crank lever consists of an arm 39 which extends into the path of lateral projection 40 on the end of arm 41 which is part of the hammer member. Another arm 42 of this bell crank lever 36 is provided with a lateral projection 43 at its lower end, this projection being adapted to engage a multi-toothed cam member 34 mounted on shaft 33 together with the ratchet wheel 32. The third arm 37 of the bell crank lever 36 extends upwardly and is provided at its upper end with a laterally projecting latching plate 38 which is adapted to engage the shoulder of the enlarged portion 23 of the manual shut-off member 19. The bell crank lever 36 is normally held in the position shown in Fig. 1 by means of the spring 44 which is coiled around shaft 35, one end being held by the hook 45 formed by a struck-out portion of the front movement plate 5, and the other end bearing against the edge of the plate 38. In this position of the bell crank lever 36, the extension 39 lies in the path of projection 40 of the hammer mechanism and the alarm cannot function.

Also journalled in the two movement plates 4 and 5 is the shaft 26 which has rigidly mounted thereon a bell crank lever 25. This lever comprises a downwardly extending arm 29 having a flat spring 30 attached to its lower end. This flat spring 30 is provided with a hole which is adapted to be engaged by the teeth of the ratchet wheel 32. The flat spring 30, therefore, functions as an operating pawl for the ratchet wheel 32. Downwardly extending arm 28 of bell crank lever 25 engages one of the spacing pillars 7 to limit the movement of the bell crank lever in a counter-clockwise direction, as viewed in Fig. 1.

The arm 29 is also provided with a laterally extending projection 31 which extends through and is adapted to engage the edge of a hole in the rear movement plate 4 in order to limit the clockwise movement of bell crank lever 25.

Bell crank lever 25 is also provided with a third arm carrying a flat laterally extending plate 24 which is located in the path of movement of the enlarged or knob portion 23 of the manual shut-off member 19. The shut-off member 19 is jour-

nalled in a bushing 20 secured in the movement holder. The spring clip 22, retained in a groove in shaft 19, limits the upward movement of the member and same is biased to its upper position by means of the spring 21 surrounding shaft 19 and bearing at its lower end against bushing 20 and at its upper end against the manual control member 17 secured to shaft 19.

The means for setting the alarm cam 55 and the alarm set indicating hand 58 comprises the shaft 62 journalled in the movement plates 4 and 5 and bearing at its lower end the gear 61 which engages the alarm gear 54. Shaft 62 at its upper end carries the gear wheel 63 which in turn is in mesh with the gear wheel 64 mounted on the sleeve 70. This sleeve 70 is rotatably mounted on and forms the bearing for the hand setting shaft 69. This shaft 69 has its lower end journalled in the movement plate 4 and mounts the gear wheel 66 which is geared into the wheel 65 mounted on center shaft 46.

From a study of Fig. 3 of the drawings, it will be seen that the sleeve 70 extends through the movement holder 3 and the gong or back cover 2, and has securely mounted thereon at its outer end, the operating knob 68. This knob is provided with a cut out portion adapted to receive a washer 71 and a nut 72 which is tightened on the threads provided on the outer end of sleeve 70 in order to clamp the knob 68 against a shoulder provided on the sleeve.

The operating knob 67 is provided with an insert 77 containing internal threads which engage the threads on the outer end of the shaft 69. As will be seen from Fig. 2, the knob 68 lies directly over the screws 9 which mount the gong to the movement holder and all unsightly mounting screws are thereby eliminated from the rear of the clock.

40 The hands of the clock are set by turning knob 67 which is geared to the center shaft 46 by means of gears 66 and 65 as previously described.

The alarm set indicating hand 58 is adjusted by means of the operating knob 68 which is geared to the sleeve carrying hand 58, through gears 64, 63, 61 and 54. The alarm cam 55 is prevented from being rotated by the cam follower 53 by means of a spring spider 78 which bears against the dial plate 6 and against a shoulder on the cam sleeve.

The operation of the alarm shut-off mechanism will now be described in connection with Figs. 4 and 5.

Fig. 4 discloses the mechanism in its "on" position, that is, with the shut-off mechanism released so that the alarm may be set in operation at the pre-determined time indicated by the alarm set indicating hand. In this position the arm 39 of bell crank lever 36 is in its lower-most position and out of the path of projection 40. The projection 43 on arm 42 is in engagement with one of the high points on the control cam 34. The manual member 17 is held in its upper-most position by spring 21 and the major portion of this member extends through the case 1 to disclose the lettering which is embossed in the member. Also, to indicate the "on" condition of the switch in the dark, the holes or wells 18 in member 17 are filled with luminous material. The member 17 may be made of transparent plastic material so that the glow of the luminous material may be seen in the dark.

When the manual member 17 is depressed, the lower knob 23 strikes the horizontal plate 24 and rotates bell crank lever 25 in a clockwise direc-

tion. During this rotation the pawl 30 engages a tooth on ratchet 32 and moves same in a counter-clockwise direction. The cam 34 moves with the ratchet wheel 32 and the projection or cam follower 43 is moved from a high point on the cam to a low point on the cam, permitting bell crank lever 36 to be rotated in a counter-clockwise direction by means of spring 44 to the position shown in Fig. 5. In this position the latching plate 38 engages the shoulder on knob 23 and holds the manual shut-off member in its lower position against the urge of spring 21. The counter-clockwise rotation of the bell crank lever 36 also brings the arm 39 into the path of projection 40, thereby stopping the sounding of the alarm.

When it is desired to turn the alarm on, the manual member 17 is again depressed, rotating bell crank lever 25 in the counter-clockwise direction and advancing the ratchet wheel 32 and associated cam 34. Rotation of cam 34 forces the cam follower 43 to a high portion of the cam thereby rotating bell crank lever 36 in a clockwise direction. This unlatches the latching plate 38 from knob 23 and permits the manual member 17 to be raised to its upper position by spring 21. In this position the word "on" is visible and also the luminous indicators are visible so that the condition of the alarm mechanism may be seen at a glance.

Clockwise rotation of bell crank lever 36 also removes arm 39 from the path of projection 40 thereby preparing the alarm mechanism so that it will operate at the set time when cam follower 53 drops into notch 76 and removes the projection 60 of spring 59 from the teeth of the alarm escape wheel 10.

From the foregoing description of the mechanism and the operation of the same, it will be seen that there is provided an improved alarm switch or shut-off mechanism for an alarm clock which is very convenient and easily operable. It will be seen that the manual operating member for the alarm mechanism is always operated in the same direction, that is, the member is depressed irrespective of whether the alarm mechanism is to be turned "on" or "off." When the mechanism is in "off" position, the manual member is in its lower-most position with only a small portion thereof extending through the case of the clock. When the alarm is in "on" position the manual member assumes its upper position in which it extends through the casing far enough to be easily grasped to shut off the alarm and in this upper-most position it also serves as a signal to indicate that the alarm switch is "on."

Although only one embodiment of the invention has been disclosed and described, it will be apparent to those skilled in the art that many modifications may be made in this mechanism without departing from the spirit of the invention.

Having described the invention, what is claimed as new and is desired to have protected by Letters Patent is:

1. In an alarm clock, alarm mechanism, an alarm shut-off member having an "off" position in which it blocks said alarm mechanism against operation and an "on" position in which it releases said alarm mechanism, a manually operable member for controlling said shut-off member, means responsive to successive operations of said manually operable member in the same direction for alternately moving said shut-off member to its "on" and "off" positions, and means as-

sociated with said last means for indicating the position of said shut-off member.

2. In an alarm clock, alarm mechanism, an alarm shut-off member having an "off" position in which it blocks said alarm mechanism and an "on" position in which it frees said alarm mechanism for operation, a manual member for controlling said shut-off member, means responsive to successive operations of said manual member in the same direction for alternately moving said shut-off member to its "on" and "off" positions, and means for latching said manual member in a partially operated position when said shut-off lever is moved to "off" position.

15 3. In an alarm clock, alarm operating mechanism, a first means for blocking said mechanism and time controlled means for releasing said first blocking means, a second blocking means for said alarm operating mechanism, a manually depressible member, means responsive to successive depressing movements of said member for alternately rendering said second blocking means effective and ineffective, and visual signal means for indicating when said second blocking means is in effective blocking position.

20 4. In an alarm clock, alarm mechanism and operating means therefor, means for blocking said operating means, time mechanism for controlling said blocking means, an alarm shut-off lever having a first position in which it blocks said alarm mechanism and a second position in which it is free of said alarm mechanism, a manually depressible member for controlling said shut-off lever, means responsive to successive depressing movements of said member for alternately moving said lever to its blocking and non-blocking positions, and means for indicating when said lever is in non-blocking position.

25 5. In an alarm clock, alarm mechanism and operating means therefor, time controlled means for controlling said operating means, blocking means for said alarm mechanism, a manually depressible member, means responsive to successive depressing movements of said member for alternately rendering said blocking means effective and ineffective, and means for retaining said member in a partially depressed position when said blocking means is effective.

30 6. In an alarm clock, alarm mechanism and operating means therefor, means for blocking said operating means, time mechanism for controlling said blocking means, an alarm shut-off lever having a blocking position and a non-blocking position with respect to said alarm mechanism, a manually operable member for controlling said shut-off lever, means responsive to successive operations of said member in the same direction for alternately moving said lever to its blocking and non-blocking positions, resilient means for urging said member to its unoperated position, and means for holding said member in a partially operated position when said shut-off lever is in blocking position.

35 7. In an alarm clock, alarm mechanism and operating means therefor, a shut-off lever for blocking said alarm mechanism, a manual member for controlling said shut-off lever, means responsive to successive operations of said member in the same direction for causing said shut-off lever to alternately block and release said alarm mechanism, means for biasing said member to a normal position, and a projection on said shut-off lever for holding said member in partially operated position when said shut-off lever is in blocking position.

8. In an alarm clock, alarm mechanism, an alarm shut-off member having an "off" position and an "on" position, a manual member for controlling said shut-off member, means responsive to successive operations of said manual member in the same direction for alternately moving said shut-off member to its "off" and "on" positions, means for latching said manual member in a partially operated position when said shut-off lever is moved to "off" position, and visual signal means associated with said manual member for indicating the position of said shut-off member.

9. In an alarm clock including a case, alarm mechanism and operating means therefor mounted within said case, control means including a manual member extending from said case for alternately blocking and releasing said operating means responsive to successive depressing movements of said manual member, signal means associated with said member to indicate the release position of said control means, and means for latching said manual member in partially depressed position when said control means is in blocking position to render said signal means ineffective.

10. In an alarm clock, alarm mechanism, a shut-off lever having an arm adapted to block said alarm mechanism, a cam for controlling the position of said arm, a manually operable member, means responsive to successive operations of said member for rotating said cam to alternately move said arm to blocking and non-blocking positions, and means associated therewith for indicating whether said arm is in blocking or non-blocking position.

11. In an alarm clock, alarm mechanism, a shut-off lever having an arm adapted to block said alarm mechanism, a cam for controlling the position of said arm, a manually operable member, means responsive to successive operations of said member for rotating said cam to alternately move said arm to blocking and non-blocking positions, and a second arm on said shut-off lever for latching said member in partially operated position when said first arm is in blocking position.

MAX E. SCHLENKER.
